UNITED STATES PATENT OFFICE.

ALBERT ATWOOD UNRUH, OF PORTLAND, OREGON.

LIFE-BUOY.

1,259,809.

Specification of Letters Patent. Patented Mar. 19, 1918.

Application filed March 2, 1917. Serial No. 151,971.

To all whom it may concern:

Be it known that I, ALBERT A. UNRUH, a citizen of the United States, residing at Portland, in the county of Multnomah and 5 State of Oregon, have invented certain new and useful Improvements in Life-Buoys; and I do declare the following to be a full, clear, and exact description of the invention, such as will enable others skilled in 10 the art to which it appertains to make and use the same.

My invention has for its principal object to provide improved stabilizing means for life buoys of the general type shown in my 15 United States Patent No. 1,119,770, issued December 1, 1914.

Another object is to provide improved means for connecting the tackle receiving rods or shackles to the buoy so as to permit 20 them to serve as supporting means for an internal platform for the lookout.

With the foregoing general objects in view, the invention resides in certain novel features of construction and in unique combinations of parts to be hereinafter fully described and claimed, the descriptive matter being supplemented by the accompanying drawings which constitute a part of this 25 application, and in which:

30 Figure 1 is an enlarged vertical section of the buoy in the position which it assumes immediately after launching;

Fig. 2 is a side elevation with the improved stabilizing means projected;

35 Fig. 3 is an enlarged vertical section through the stabilizing means showing the same in the retracted position of Fig. 1;

Fig. 4 is an enlarged sectional view of 40 part of the stabilizing means in extended position;

Fig. 5 is a horizontal section on the plane of the line 5—5 of Fig. 3;

Fig. 6 is a similar view with the stabilizing plates swung upwardly;

45 Fig. 7 is a detail vertical section on the plane of the line 7—7 of Fig. 5; and

Fig. 8 is a similar view on the plane indicated by the line 8—8 of Fig. 6.

In the drawings above briefly described, 50 the numeral 1 has reference to a suitable shell preferably formed of sheets of metal riveted or welded together around an appropriately constructed skeleton frame 2, the upper portion of the shell 1 being in 55 the form of a conning tower 3 having a vertically moving ventilator cap 4, a plurality

of colored signal lights 5, and other lights 6 for the lookout. Electric bulbs 7 are preferably located adjacent the signal lights 5 so as to illuminate the latter at night to render the floating buoy visible to other ships 60 which may be in the vicinity.

The ventilator 4 is carried by the upper end of a stem 8 whose lower end is pivoted to a lever 9 fulcrumed at one end within the 65 conning tower 3 and guided at its other end in the slot 10 of a vertical guide bar 11, this last named end of the lever being by preference provided with a depending handle 12 by means of which it may be operated to 70 open and close the ventilator 4 as occasion may demand.

Within the shell 1 are two or more superimposed annular seats 13 whose backs are by preference formed of a suitable mesh 75 screen wire 14. These seats will by preference be provided with partitions so as to provide separate compartments for the several occupants and will in most cases be equipped with suitable straps whereby they 80 may be strapped in their individual seats if required. Above the uppermost seat 13 is a step 15 located below the lower end of a hatchway 16 by means of which the passengers enter the buoy, said hatchway being 85 equipped with a suitable watertight door 17 as will be clear from the drawings. In case of leakage at this door, however, or at any other point, a pump 18 is preferably provided, the lower end of said pump being 90 screened and located in a depression 19 in the bottom of the shell 1.

The interior of the buoy will be equipped with sufficient provisions and fresh water to last the occupants several days, and first aid 95 necessities such as medicine chests and the like will be provided. Among the other accessories provided for the convenience of the occupants is a marine toilet fixture 20 located in a suitable compartment 21.

100 Another appliance by preference employed is a ventilating pipe 22 and fan 23, the former leading downwardly from the ventilator 4 so that by means of any of the well known automatic controls, the fan 23 may 105 be made to draw in fresh air and expel foul air at suitable intervals.

A shackle 24 is provided at the upper end of the conning tower 3 to permit the attachment of a tackle in lowering the buoy from 110 a vessel or in lifting it on board, said shackle being formed of two arched rods 25 whose

crowns cross each other as shown, the two halves of said rods passing through the top of the tower 3 and extending to the bottom of the shell 1, at which point they are suitably anchored. Both halves of the rods 25 are preferably formed of upper and lower sections connected at a suitable point by turn buckles 26, and these buckles may well serve as supports for a platform 27 through which the rods pass, said platform being designed primarily to be occupied by the lookout, although it may be used for other purposes such for instance as a support for the fan 23. Steps 28 preferably lead to the platform 27 but the use of these is optional since other means may well be employed in lieu thereof.

An annular apron 30 depends from the bottom of the buoy and is provided between its ends with a horizontal partition 31 co-operating with said bottom to provide a water ballast chamber 32, said chamber having a suitable number of water inlets 33, and a number of vents 34 for allowing the escape of air as the water enters. The apron, below the partition 31, constitutes a housing or pocket to normally receive therein the stabilizing plates and vanes yet to be described, the vertical shaft on which said plates and vanes are carried being slidably mounted in an upright tubular guide formed of upper and lower pipes 35 and 36. Pipe 35 extends from the bottom of the buoy to the platform 27, while pipe 36 depends from said bottom to the partition 31.

A vertical shaft 37 is provided, said shaft consisting of a plurality of telescoping sections 38 equipped with suitable collars 39 to limit the extensibility of said shaft, said collars having teeth 40 which interengage when the shaft is extended so as to prevent relative rotation of the several sections. The innermost section 38 is connected at its upper end with a cable 41 which passes through a central opening in a partition 42 in the upper end of the pipe 35 and then over a pulley 43, said cable being connected with an appropriate drum 44 whereby it may be wound or paid out as occasion may demand.

A plurality of upstanding vanes 45 radiate from the lower end of said innermost section 38 and at their inner ends are secured thereto preferably by angle irons 46. The outer ends of the vanes 45 are held in spaced relation by arcuate bars 47 extending therebetween and secured thereto, said bars 47 and angle metal ledges 48 projecting from the inner section 38, serving to receive thereon and support segmental stabilizing plates 49 which at 50 are hinged to the vanes 45. By connecting the plates 49 with the vanes in this manner, said plates may fold upwardly to the position shown in Figs. 6 and 8 when the cable 41 is released to allow the shaft 37

to drop by gravity to the operative position shown in Figs. 2 and 4, and thus said plates will offer no resistance to the quick projection of said shaft. Having reached the limit of their downward movement, the plates 49 will swing downwardly to the horizontal position of Figs. 3 and 5 so that they form a complete disk which co-operates with the vanes 45 in forming an effective stabilizing means acting more or less as a center board, the buoy being thus prevented from bobbing around on the surface in the manner which is unavoidable when no such stabilizing means is employed.

The improved buoys are adapted to take the place of the usual open life boats now used on both passenger liners and freighters, each vessel being equipped with an adequate number to accommodate passengers and crew. These buoys will be supplied with food, water, and other necessities, and will be so located as to permit them to be readily dropped over the side of the ship. With the vessel thus equipped, assuming that the same is torpedoed or otherwise injured so that sinking is unavoidable, the passengers are loaded into the several buoys and are by preference strapped in their individual seats. This having been done the hatchway 17 is closed and the buoy is dropped over the side of the ship. Either now or beforehand, but preferably after the buoy is launched, the drum 44 is released so as to permit the shaft 37 to drop by gravity to extended position whereupon the stabilizing plates 49 and the vanes 45 will come into play to prevent the buoy from being excessively tossed about on the waves. A lookout will be stationed on the platform 27 so that approaching vessels may be seen through the lights 6, and from time to time he will open the ventilator 4 and start up the fan 23 so as to expel the foul air from and admit fresh air into the buoy, thus insuring that none of the occupants will suffer for want of an adequate amount of oxygen. By night the colored lights 5 which are preferably red, will be displayed, whereas in the day time a flag will be visible so that the several buoys may be readily seen from any ships which may be in the vicinity and they may thus come to the aid of the survivors.

From the foregoing, taken in connection with the accompanying drawings, the construction, manner of operation, and advantages of the invention will be clear and it will be obvious that although the improved buoy is of rather simple, inexpensive, and light construction, it will be a highly efficient and durable life saver. For these reasons the arrangement shown constitutes the preferred form of the buoy but it is to be understood that within the scope of the invention as claimed, numerous changes

may be made without sacrificing the principal advantages.

I claim:—

1. The combination with a life buoy, of a vertically disposed shaft carried thereby and normally retracted, said shaft being adapted to be projected downwardly when the buoy is launched, and stabilizing means carried by the lower end of said shaft and including a plurality of radiating upstanding vanes, and plates hingedly mounted between said vanes, said plates being adapted to swing upwardly when the shaft is being lowered and to then assume substantially horizontal 15 positions.

2. The combination with a life buoy, of a vertically disposed shaft carried thereby and normally retracted, said shaft being adapted to be projected downwardly when the buoy is launched, and stabilizing means carried by the lower end of said shaft and including a plurality of upstanding vanes radiating therefrom, and segmental plates hinged to said vanes, said plates being 20 adapted to swing upwardly when the shaft is being lowered and to then assume substantially horizontal positions.

3. The combination with a life buoy, of a vertically disposed shaft carried thereby and normally retracted, said shaft being adapted to be projected downwardly when the buoy is launched, and stabilizing means carried by the lower end of said shaft and including a plurality of upstanding vanes radiating therefrom, bars extending between and secured to the outer ends of said vanes to hold the same in spaced relation, and segmental stabilizing plates hingedly mounted between said vanes, said plates 35 being adapted to swing upwardly when the shaft is being lowered and to then drop by gravity onto said bars.

4. The combination with a life buoy, of a

telescopic shaft carried thereby and normally retracted, the lower end of said shaft 45 having stabilizing means operative when said shaft is extended, coacting stop collars on the several shaft sections for limiting the extension of the shaft, and interengaging teeth on said collars for preventing relative 50 turning of the several sections of said shaft.

5. The combination with a life buoy, of a shackle at the upper end thereof formed of a plurality of arched rods crossed at their crowns, both halves of said rods extending 55 through the interior of the buoy and being anchored to or near the bottom thereof, and a platform supported by said rods and located within the buoy.

6. The combination with a life buoy, of a shackle at the upper end thereof formed of a plurality of arched rods crossed at their crowns, both halves of said rods extending 60 through the interior of the buoy and being anchored to or near the bottom thereof, 65 supporting members on said rods within the buoy and a platform resting on said members, said platform having openings through which the rods pass.

7. The combination with a life buoy, of a telescopic shaft carried thereby and normally retracted, the lower end of said shaft 70 having a stabilizing means operative when said shaft is extended, coacting stop collars on the several shaft sections for limiting 75 the extension of the shaft, and interengaging means on said collars for preventing relative turning of the several sections of said shaft.

In testimony whereof I have hereunto set 80 my hand in presence of two subscribing witnesses.

ALBERT ATWOOD UNRUH.
